UNITED STATES PATENT OFFICE

GUY RABY, OF VERMONT, ILLINOIS

WHEEL-CLEANING ATTACHMENT FOR TRACTORS

Application filed November 7, 1927. Serial No. 231,596.

This invention relates to a wheel scraping attachment designed primarily for use in connection with tractors, one of the objects being to provide a simple and efficient device 5 of this character which is cheap to manufacture and which can be applied readily to a tractor without requiring the services of a skilled mechanic.

A further object is to provide a device 10 formed of the minimum number of parts capable of withstanding rough usage and operating efficiently under all conditions.

With the foregoing and other objects in view which will appear as the description 15 proceeds, the invention resides in the combination and arrangement of parts and in the details of construction hereinafter described and claimed, it being understood that changes 20 in the precise embodiment of the invention herein disclosed may be made within the scope of what is claimed, without departing from the spirit of the invention.

In the accompanying drawing, which is a perspective view, the attachment has been 25 shown applied to a tractor a portion of which has been illustrated.

Referring to the drawing by characters of reference 1 designates brackets having integral sleeves 2 which are split transversely 30 as indicated at 3 for the reception of collars 4 carried by a transverse shaft 5. These collars are held against longitudinal movement relative to the shaft by means of set screws 6 and constitute means for holding the shaft 35 against longitudinal displacement relative to the sleeves 2. The ends of the shaft project laterally beyond the sleeves and mounted on them are sleeves 7 each having an integral blade 8 projecting therefrom. Set screws 9 40 or the like are employed for holding the sleeves 7 against movement relative to the shaft 5. The blades are so proportioned and located as to extend between the cleats C on the wheels W of the tractor. An arm 10 is 45 extended from the shaft 5 and has a coiled spring 11 attached to the free end portion thereof, this spring being extended under the shaft 5 and connected to a portion of the tractor so as to be normally under tension. 50 Brackets 1 can also be attached to any desired

portions of the tractor, such as the fenders F. In using the device the brackets are secured in place and the spring 11 is also attached to the tractor. The sleeves 7 are adjusted along the shaft 5 so as to bring the blades 8 to positions where they will work between the cleats C. The pull of the spring 11 on the arm 10 will cause these blades to bear firmly against the peripheries of the wheels. The blades will incline upwardly and rearwardly relative to the wheels and it will be apparent that, when these wheels rotate, the said blades will act to wedge back of accumulations of soil carried by the rims of the wheels and push them backwardly off of the cleats so as to leave the cleats practically clear and maintain them at maximum efficiency.

What is claimed is:

A wheel cleaning attachment for tractors including attaching brackets for engagement 70 with opposed fenders of a tractor, spaced integral sleeves extending from each bracket, a rock shaft journaled in all of the sleeves and adapted to extend transversely of a tractor, collars adjustably mounted on the shaft and 75 interposed between the sleeves on each bracket, thereby to hold the shaft against longitudinal movement relative to the brackets, said brackets and collars being adjustable along the shaft for positioning the 80 brackets on fenders at different distances apart, scraping blades, a sleeve on one end of each blade into which one end of the shaft projects, means carried by the sleeve for binding it on the shaft, thereby to insure rotation of the blade with the shaft, said blades being adjustable toward and from each other on the shaft, an arm radiating from the shaft, and a spring for connecting the arm to a portion of a tractor thereby to hold the blades 85 pressed yieldingly against the periphery of the tractor wheels.

In testimony that I claim the foregoing as my own, I have hereto affixed my signature.

GUY RABY. 95
